UNITED STATES PATENT OFFICE.

BENJAMIN H. ALVEY, OF ELIZABETHTOWN, KENTUCKY.

ROTARY ENGINE.

1,151,430.

Specification of Letters Patent. Patented Aug. 24, 1915.

Application filed December 18, 1912. Serial No. 737,413.

To all whom it may concern:

Be it known that I, BENJAMIN H. ALVEY, a citizen of the United States, residing at Elizabethtown, in the county of Hardin 5 and State of Kentucky, have invented new and useful Improvements in Rotary Engines, of which the following is a specification.

This invention relates to improvements in 10 rotary engines and particularly to that type of such engines wherein the rotor or piston is associated with a rotary abutment. This invention aims to improve the operation and increase the efficiency of engines of this type, 15 by providing means of most satisfactory character for the operation of the rotary abutment at proper times in the revolutions of the rotor and for effectively locking said abutment against forward or retrograde 20 movement at other times.

Other purposes and advantages of the present invention will be understood from the hereinafter description of the preferred embodiment thereof.

25 In the accompanying drawings illustrating said preferred embodiment and wherein like characters of reference denote like parts in the several views: Figure 1 is a vertical longitudinal section through an engine having 30 two rotors or pistons mounted on a common shaft. Fig. 2 is a side elevation of the operating mechanism of the engine, the casing being shown in section to disclose said mechanism. Fig. 3 is a vertical transverse section on the line 3—3 of Fig. 1. Fig. 4 is a 35 vertical transverse section on the line 4—4 of Fig. 1. Fig. 5 is a detail representation of the back stop for the rotary abutment.

The present invention is preferably, 40 though not essentially, embodied in an engine having a plurality of rotors, and, therefore, it is exemplified in an engine having two rotors, this being a very desirable number.

45 The casing embodies chambers of appropriate number, size and relative location for the operative parts which are to be incased. In the present exemplification, there are chambers A' and B' for the rotors A 50 and B, respectively, chambers C' and D' for the rotary abutments C and D respectively, and a chamber E for various operating elements hereinafter more particularly set forth. There is also a steam-chamber F ar-

ranged between the chambers A' and B' and 55 having communication with the latter through steam-inlet ports f and f', respectively. The chambers A' and B' also have exhaust ports a' and b'.

G designates the main shaft of the engine. This shaft extends through the chambers A', E and B' and has suitable bearings in the walls thereof. It also preferably has a bearing in the chamber E, the latter bearing being marked H. This bearing 65 preferably is arranged at about the longitudinal center of the chamber E, and has one or more oil passages h whose ends open 70 into the compartments e, e' of the chamber E, said compartments being arranged on opposite sides of the bearing. In practice, the chamber E contains oil and serves as a reservoir therefor, whereby the operating parts mounted therein run in oil and hence 75 are effectively lubricated.

The rotors A and B are fixedly secured to the shaft G and communicate motion thereto. Each is of the usual or any suitable construction, comprising a body 10 and a projection or piston head 11.

80 The abutments C and D are mounted respectively on shaft I and J, having confronting inner ends journaled in suitable bearings at K, preferably mounted on top of the steam chamber F. The portions of the 85 shafts between the chambers A' and B' are preferably incased, as shown at K'. Each abutment has an appropriate number of radiating arms or vanes 12 which extend 90 into the path of the pistons 11 a distance 95 which causes the particular vane which is operating as an abutment to make contact with the circumference of the body 10 of the rotor, so as to prevent leakage of steam thereby while the piston 11 is receiving the force of steam, under pressure.

100 Each of the abutments is positively operated at predetermined times by the means hereinafter described, and each is locked against movement at other times by a sliding stop 13 and a back stop 15 which are normally projected into the path of travel 105 of the arms or vanes 12 preferably in such position that one stop will engage the forward surface of one arm or vane while the other stop will engage the rearward surface of the next succeeding arm or vane. They are movable out of said path in order to

permit the abutment to be turned. The inlet ports f and f' are controlled by slide-valves 17 and 18, respectively.

The rotary abutments C and D, the sliding lock stops 13 and the slide valves 17 and 18 are operated positively, at predetermined times in the travel of the pistons 11, from the portion of the main shaft G mounted in the chamber E, said portion of the main shaft being provided with suitable elements, as eccentrics, cams, or the like, having portions eccentric to their axes, which operate appropriate mechanism for transmitting properly timed movements to the several parts named. A most desirable and, therefore, the preferred means for this purpose will now be described.

Fixedly mounted on the portion of the main shaft G within the chamber E are a series of eccentrics, one for each sliding valve 17, 18, one for each sliding lock stop 13 and one for each rotary abutment-shaft I, J. In the present exemplification of the invention there are six of said eccentrics shown, and they are marked 19, 20, 21, 22, 23 and 24 respectively. Those illustrated are of the style which are associated with eccentric straps engaging the peripheral surfaces thereof. The eccentrics 19 and 20 operate the sliding valves 17 and 18, the lower ends of said valves being suitably connected, as by the pivots 25 and 26 to the eccentric straps 19^a and 20^a, respectively. The eccentrics 21 and 22 operate the sliding lock stops 13, said lock-stops being provided with racks 14 which are engaged by gears 27 and 28 fixed on oscillatory shafts 29 and 30. These shafts are provided with crank arms 31 and 32 which are connected by links 33 and 34 with the upper ends of levers or eccentric rods 35 and 36, whose lower ends are suitably connected to the eccentric straps 21^a and 22^a, respectively. Each lever or rod 35, 36 is fulcrumed between its ends upon a bracket 37, said bracket having a projection 38 which extends into an elongated slot 39 in the lever or rod and serves as a pivot for the latter. The eccentrics 23 and 24 operate the rotary abutments C and D. The shafts I and J of said abutments are provided with star wheels 40 and 41 which are keyed thereon, respectively. The radial arms or teeth, 40^a, 41^a of the star wheels are engaged by inward projections 42^a, 43^a from the upper ends of arms or levers 42, 43 which are suitably connected with the eccentric straps 23^a and 24^a respectively. It will be understood that the radial arms or teeth of the star wheels correspond in number and position with the radial arms or vanes of the abutments and that the abutment shafts are intermittently moved one step at each rotation of the main shaft. The arms or levers 42 and

43 extend through suitable guides 44, 45 65 and are engaged by springs 46, 47 for assuring proper operation thereof.

Each back stop is preferably pivoted at 48 in a recess formed in the adjacent wall of the casing and is spring pressed outward 70 from said recess so as normally to engage the rear surface of the adjacent vane or arm of the abutment. This construction permits the back stop to be pressed into its recess by said vane or arm during the 75 rotative movement of the latter and then to spring out behind said arm or vane as soon as the latter has passed, so as to prevent retrograde movement of the abutment under the pressure of the incoming steam. 80

In practice, the parts are so correlated that the induction port of each chamber is closed when the piston associated therewith is passing from the exhaust port to said induction port, during which time the 85 sliding lock stop of the abutment associated with said piston is fully retracted and the abutment is turned, said abutment pressing its back stop 15 out of the way and said back stop automatically springing out to 90 lock the abutment against retrograde movement when the slide valve commences to open.

It will be understood that the pistons of the rotors A and B are set in a following 95 relation with respect to each other, being preferably set on halves, and that the slide valves 17 and 18 are moved successively to uncover the respective ports f and f' , whereby one is being closed while the other is 100 being opened. It is preferred that the parts be so arranged that each slide valve commences to close when the piston in the chamber associated with said valve has made three-fourths of a complete revolution, indicated at X, Fig. 4, and fully closes the induction port to said chamber somewhat before the piston has completed its revolution and covering said port until the piston has passed beyond the point at which it 110 completes its revolution and into the next revolution, whereupon it commences to uncover the induction port and fully uncovers the same when the piston has made one-fourth of one revolution. 115

It will be noted that in the present exemplification of the invention, the slide valves move upwardly beyond the induction ports, into offsets marked 50, 51 and that during its up and down movements in said offsets the induction ports are fully closed. The retractile movement of each lock stop may commence when the piston has reached the three-quarter place X, and the stop is preferably out of engagement with the abutment 125 when the piston reaches the place marked Y, Fig. 4. The induction port being now closed and the abutment released, the abutment is

turned and by the time it reaches the position at which the arm or vane succeeding that which formerly received the steam pressure has been brought into operative position, the sliding lock stop has again advanced into position to hold the abutment, completing its advancing movement, if desired, while the induction port is being opened to its full extent. The inclined surfaces 11^a of the pistons may operate to assist the eccentrics to turn the abutments, if desired. Again, it is not wholly essential to the present invention that the entire turning movement of the abutments be accomplished 15 while the induction ports are fully closed, but the arrangement described is preferred for the reason that it overcomes the disadvantage of waste of steam, it being apparent that if the induction port and the exhaust 20 port are both open while the piston is between the same, the inflowing steam will flow through the exhaust port without acting upon the piston. If desired the pistons may have circumferential surfaces of such 25 length as to serve as cut-offs for the exhaust ports during a predetermined portion of the revolution of the pistons within which the pistons travel over the exhaust port, it being preferred in such case that the prolonged 30 parts be so formed that their sides will not act as cut offs for the induction ports.

It will be noted that the parts are positive in their action, all running parts needing oil may be effectively and economically supplied therewith, and that all parts needing 35 to be packed may be readily and easily packed. In short, the engine herein described is simple and efficient in its construction, in the highest degree.

From the foregoing the purposes and advantages of the present invention and the structure and operation of the herein exemplified embodiment thereof will be apparent, and it will be readily understood 40 that changes may be made in this particular embodiment without departing from the spirit of the invention or the scope of the subjoined claims.

Having now described the invention what 45 I believe to be new and desire to secure by Letters Patent, is:—

1. In a rotary engine, the combination with a rotary piston and a rotary abutment, said abutment having spaced arms or vanes, 50 of means for locking the abutment against rotation comprising a reciprocatory stop arranged to be intermittently projected into the spaces between the arms or vanes and to prevent rotation of the abutment by engaging the surface of the adjacent arm or vane, the said stop being also arranged to be retracted to permit movement of the abutment, means for moving said stop into its said projected and retracted positions

at predetermined times in the movement of 65 the piston, and means for turning the abutment when the stop is retracted.

2. In a rotary engine, a shaft, a rotor mounted thereon, a reciprocatorily mounted stop, a rotary abutment having arms or 70 vanes spaced from each other, eccentrics on the rotor-shaft, and connections between the eccentrics and the stop and abutment, respectively, the parts being so arranged that the stop will be projected into the space between a pair of arms or vanes and will be retracted from said space at predetermined times, independently of the movement of 75 the abutment.

3. In a rotary engine, the combination 80 with a rotary piston, its shaft and a rotary abutment, said abutment having spaced arms or vanes, of means for locking the abutment against rotation, said locking means comprising a reciprocatory stop having 85 teeth, a gear to engage said teeth and means for oscillating said gear at predetermined times in the travel of the piston.

4. In a rotary engine, the combination with a rotary piston, its shaft, and a rotary 90 abutment, said abutment having spaced arms or vanes, of means for locking the abutment against rotation, comprising a reciprocatory stop having teeth, a rock shaft, having a gear to engage said teeth and 95 means operated from the piston shaft for oscillating said rock shaft intermittently at predetermined times in the travel of the piston.

5. In a rotary engine, the combination 100 with a rotary piston, its shaft, and a rotary abutment, said abutment having spaced arms or vanes, of means for locking the abutment against rotation, comprising a reciprocatory stop having teeth, a rock-shaft 105 having a gear to engage said teeth, a crank arm projecting from said rock-shaft, an operating element mounted on the piston shaft and provided with a portion eccentric to its axis, and means operated by said element 110 and connected with said crank arm for oscillating the rock-shaft at predetermined times in the travel of the piston.

6. In a rotary engine, the combination with a rotary piston, its shaft, and a rotary abutment, said abutment having spaced arms or vanes, of means for locking the abutment against rotation, comprising a reciprocatory stop having teeth, a rock-shaft having a gear to engage said teeth, a crank arm projecting from said rock-shaft, an operating element mounted on the piston shaft and provided with a piston eccentric to its axis, a rod having connection with said element and provided with a slot between its ends, 115 a fixed pin extending into said slot, and a link connecting the rod with the crank arm. 120

7. In a rotary engine, the combination of

a rotary piston, a rotary abutment having spaced arms or vanes, shafts for the piston and abutments respectively, means connecting the abutment shaft and piston shaft, 5 front and back stops, the former of which engages the forward surface of one arm or vane and the other engages the rear surface of an arm or vane, and means through which steam is admitted between a pair of 10 arms or vanes.

8. In a rotary engine, the combination with a rotary piston, a rotary abutment having spaced arms or vanes, and means for rotating the abutment at predetermined 15 times in the travel of the piston, of means for locking the abutment against rotation at other times, comprising a slidable stop and a spring-pressed stop respectively arranged to engage opposite surfaces of successively arranged arms or vanes, and means 20 for positively reciprocating the slidable stop at predetermined times in the travel of the piston, the spring-pressed stop being arranged to be pressed out of the path of the 25 arms or vanes by the latter when the abutment is being rotated by its rotating means.

9. In a rotary engine, a rotary piston, its shaft, and a rotary abutment having arms or vanes, and means for intermittently turning 30 the rotary abutment at predetermined times in the movement of the piston, comprising a wheel fixed on the abutment shaft and provided with projections corresponding in number and location with the arms 35 or vanes of the abutment, an operating element mounted on the piston-shaft and provided with a portion eccentric to its axis, a rod having connection with said element and having an end arranged to engage the 40 teeth of said wheel, a guide for said rod, and a spring for pressing the rod toward the wheel.

10. In a rotary engine, a casing having an induction port and an exhaust port, a rotary 45 piston in said casing, a piston-shaft, a rotary abutment in said casing, having arms or vanes, an abutment-shaft, a wheel on the abutment-shaft, having teeth corresponding to the arms or vanes of the abutment, a 50 locking means for the abutment, comprising a reciprocatory stop, a rack connected to said stop and an oscillatory shaft having a gear connected with said rack, a reciprocatory valve for controlling the induction 55 port, and means operated from the piston shaft for reciprocating said valve, oscillating the oscillatory shaft and turning the wheel of the abutment-shaft, intermittently, at predetermined times in the movement of 60 the piston.

11. In a rotary engine, a casing having an induction port and an exhaust port, a rotary piston in said casing, a piston-shaft, a rotary abutment in said casing, having arms

or vanes, an abutment shaft, a wheel on the 65 abutment-shaft, having teeth corresponding to the arms or vanes of the abutment, a locking means for the abutment, comprising a reciprocatory stop, and a reciprocatory valve for controlling the induction port, 70 combined with means whereby the valve, abutment and reciprocatory stop are positively operated from the piston shaft at predetermined times in the movement of the piston, said means comprising operating 75 elements mounted on the piston shaft and having portions eccentric to their axes, a connection between one of said elements and the valve, means actuated from another of said elements for turning the wheel of the 80 abutment shaft intermittently, a rack connected to the reciprocatory stop, an oscillatory shaft having a gear engaging said rack, and means connecting the oscillatory shaft with another one of said elements. 85

12. In a rotary engine, casings spaced from each other and each provided with a rotor chamber and an abutment chamber, said casings having induction ports leading to the rotor chambers, a shaft extending 90 through said rotor chamber and across the space between the same, rotors fixed on said shaft and mounted in the rotor-chambers, rotary abutments in the abutment chambers, valves for controlling the induction ports 95 and means mounted on the portion of the shaft between the casings for positively operating the valves and abutments at predetermined times in the movements of the pistons. 100

13. In a rotary engine, casings spaced from each other and each provided with a rotor chamber and an abutment chamber, a steam chest arranged between said casings, induction ports leading from said steam 105 chest to the rotor chambers, a shaft extending through said rotor chambers and across the space between the same, rotors fixed on said shaft and mounted in the rotor chambers, rotary abutments in the abutment-chambers, shafts for said abutments, having bearings upon the steam chest, valves for controlling the induction ports and means mounted on the portion of the shaft between the casings for positively operating the 110 valves and abutment-shafts at predetermined times in the movements of the pistons. 115

14. In a rotary engine, casings spaced from each other and each provided with a 120 rotor chamber and an abutment chamber, said casings having induction ports leading to the rotor chambers, means forming an oil chamber between said casings, a shaft extending through said rotor-chambers and oil chambers, a bearing for said shaft in the oil chamber, rotors fixed on said shaft and mounted in the rotor-chambers, ro-

tary abutments in the abutment chambers, reciprocatory valves for controlling the induction ports, and means mounted on the portion of the shaft within the oil chamber 5 for positively operating the valves and abutments at predetermined times in the movements of the pistons.

In testimony whereof I have hereunto set my hand in presence of two subscribing witnesses.

BENJAMIN H. ALVEY.
